UNITED STATES PATENT OFFICE.

MARCUS ALLEN STICKLEY, OF STRASBURG, VIRGINIA.

WIRE STRETCHING AND SPLICING DEVICE.

1,172,071.

Specification of Letters Patent. Patented Feb. 15, 1916.

Application filed April 26, 1915. Serial No. 24,059.

To all whom it may concern:

Be it known that I, MARCUS A. STICKLEY, a citizen of the United States, residing at Strasburg, in the county of Shenandoah and

5 State of Virginia, have invented certain new and useful Improvements in Wire Stretching and Splicing Devices, of which the following is a specification.

The present invention appertains to improvements in wire working tools, and especially as adapted for splicing and stretching wires, in which processes my invention is adapted to facilitate the operations of loop forming and twisting of the wire.

15 In carrying out the invention, I provide a pair of tool elements which coact in the preliminary step of the operation in that one of said elements constitutes holding means for the wire while the other performs the 20 function of a twisting lever and in the further step of joining together wire strands, the first-mentioned element acts as the tighter or twisting means while the second cooperates therewith to form a bearing in 25 the stretching operation and a loop forming lever and stop in the final wrapping action of the looped end.

For a full understanding of the present invention reference is to be had to the following description and the accompanying drawing, in which:

Figure 1 is a view in elevation showing the coöperation of the tools in the preliminary step of fastening together wire strands. 35 Fig. 2 is a plan view showing the members in coöperative relation in the subsequent step of stretching and fastening the wire ends. Fig. 3 is a sectional view taken on the plane indicated by the line 3—3 of Fig. 2 but with the loop forming lever raised to a vertical position. Fig. 4 is a view in elevation as indicated by the plane line 4—4 of Fig. 3. Fig. 5 is a perspective view of the joined ends of wire strands as connected 40 by means of my device.

Throughout the following detail description, and on the several figures of the drawing, similar parts are referred to by like reference characters.

50 Specifically describing the device and referring to the drawing, A designates the tool element which, for the purposes of this description will be called the wire holding member or stretching means, said member 55 comprising a shank 1 of suitable length and size having at one end a handle or grip 2.

The shank 1 at an intermediate point is formed with a transverse opening 3 which is adapted to receive the end of a wire in the manner to be more clearly hereinafter set forth. Projecting from the handle 2 parallel with the shank and in spaced relation thereto is a wire-engaging arm 4. The other of the tool elements which constitutes the subject-matter of my invention is designated B, and this member is formed at one extremity with offstanding spaced lugs 5 and adjacent to the same extremity with oppositely offstanding projections 6 at the edge of the member.

In the use of the invention only one of the projections 6 is requisite but two are provided in order to enable right-hand or left-hand twisting operations with this member. Because of its peculiar coaction with the member A, the element B is, for the purposes of this description, termed a loop-forming lever. The lever or member B is further formed at its opposite extremity with a notched or forked portion designated 7, and adjacent to this end is a wire-receiving opening 8 that may be used as found convenient in performing the function of splicing or repairing wires.

Describing the use of the foregoing tool or tool elements and assuming that it is desired to repair a broken wire or to splice a wire as the case may be, the end of one wire strand 9 is bent about the arm 4 of the element A, whereupon the lever B is disposed with its guide lugs 5 engaging the wire and with one of the shoulders or projections 6 engaging the wire end so that rotation of the member B about the wire 9 will wrap or twist the wire extremity, as most distinctly shown in Fig. 1. Obviously the member A holds the wire during the twisting action hereinbefore described. After the formation of this loop the end of the other strand 10 which is to be joined to the wire 9 is passed upwardly through the loop of the wire 9 and introduced into the opening 3 of the shank 1 of the member A. The member B is thereupon seated upon the wire in the prone position shown in Fig. 2 with the guide lugs 5 at one end straddling the wire 9 and with its opposite forked end engaging beneath the shank 1 on the loop of this wire 9 so as to form a bearing seat. The rotation of the member A will obviously draw the wire 10 through the loop until the proper tension is obtained, the

wire incidentally being wrapped about the shank of the member A in the manner as clearly shown in Fig. 2. During this drawing of the wire 10 through the connecting loop, the forked end holds the loop from being bent out of alinement, thereby preventing breakage if the wire should happen to be rusty. In the use of splicing tools of known types, one of the troublesome defects when this point in the joining operation is reached, is the fact that it is difficult to proceed with the completion of the joining operation without losing tension on the wires obtained by the preliminary steps 10 and this is the difficulty which my tool is especially designed to overcome. As before stated, having obtained the proper tension upon the wire strands 9 and 10, the member B is raised into vertical position such 20 as shown in Fig. 3, said member fulcruming about the end of the looped extremity of the wire 9, this lifting action actuating the wire stretching member A so as to form a loop in the extremity of the wire 10. Obviously no release of the tension has taken 25 place since the member A is held from rotation, during this action by the operator and when the member B is positioned vertically the forked extremity 7 thereof straddles the looped end of the wire 10 so that the wires will be prevented from turning when the wrapped end on the shank of the member A is twisted about the wire 10 by rotation of said member around the wire 30 and simultaneous unwrapping of the extremity therefrom. When the foregoing operation has been completed the joined ends 35 will appear somewhat as shown in Fig. 5.

It will be apparent that the tool elements 40 constituting my invention will enable the performance of the above described operation in close places and where the wire strands are close together as in fences comprising a plurality of wire strands. While 45 the illustration in the drawing shows the joining together of two wire ends, it will be obvious that the splicing of wires by the use of an inserted splice wire may be just as readily accomplished in the manner described. 50

Having thus described my invention, what I claim as new is:

1. In a device of the class described, the combination with a stretching member comprising a shank having an opening to receive the wire to be stretched, of a coöperating bearing member adapted to rest upon a wire to be connected to the wire before mentioned and to form a bearing seat for the shank 55 aforesaid during rotation thereof in the stretching operation, said bearing member having a wire-engaging extremity for holding the wire on which it rests in alinement during said stretching action. 60

2. In a device of the class described, the

combination with a stretching member comprising a shank having an opening to receive the wire to be stretched, of a coöperating bearing member adapted to rest upon a wire provided with a connecting loop and to form a bearing seat for the shank aforesaid during rotation thereof in the stretching operation, and means on one end of said bearing member to hold it from lateral displacement from the wire, the other end having a loop-engaging fork for holding the loop aforesaid from distortion during drawing of the stretching wire therethrough. 75

3. In a device of the class described, the combination with a stretching member comprising a shank having an opening to receive the wire to be stretched, of a coöperating bearing member adapted to rest upon a wire and to form a bearing seat for the shank aforesaid during rotation thereof in the stretching operation, said bearing member constituting a lever for actuating the stretching member when the wire is stretched to bend the wire in forming a connecting loop. 85

4. In a device of the class described, the combination with a stretching member comprising a shank having an opening to receive the wire to be stretched, of means to engage the stretching member for bending the wire to form a connecting loop when the wire is under tension, said means constituting a stop to prevent loss of said tension during fastening of the looped end. 95

5. In a device of the class described, the combination with a stretching member comprising a shank having an opening to receive the wire to be stretched, of a coöperating bearing member adapted to rest upon a wire and to form a bearing seat for the shank aforesaid during rotation thereof in the stretching operation, the bearing member also forming a stop to prevent slipping of said wire during wrapping of the looped end by the stretching member. 100

6. In a device of the class described, the combination with a stretching member having an opening adapted to receive one end of a wire strand, of a lever engageable with the end of a wire to which the first end is to be joined, said lever fulcruming against the wire end with which it engages to actuate the stretching member to bend the wire for forming a connecting loop, said lever having a forked extremity to engage said loop whereby to prevent turning of the wire during engagement of the looped end by the stretching member. 115

7. In a device of the class described, the combination with a stretching member comprising a shank having an opening to receive the wire to be stretched and a handle at one end, of a loop-forming lever for coöperation with said stretching member and comprising spaced lugs projecting therefrom for hold- 120

130

ing said member in position upon a wire in the stretching operation, and a forked extremity for engaging the wire to be stretched to hold the same from turning during engagement with the wire by the stretching member.

8. Means for forming wire loops, comprising an axially rotative tool element having

engagement with the end of a wire and adapted to coöperate with a slotted plate 10 adapted to engage the loop and the tool element to bend the wire into alinement while holding said wire during rotation of the tool element for fastening the end of the wire.

In testimony whereof I affix my signature.
MARCUS ALLEN STICKLEY.
